UNITED STATES PATENT OFFICE.

HARRY Y. ARMSTRONG, OF SPRINGFIELD, MASSACHUSETTS, ASSIGNOR TO PACKAGE MACHINERY COMPANY, OF SPRINGFIELD, MASSACHUSETTS, A CORPORATION OF MASSACHUSETTS.

WRAPPING-MACHINE.

1,292,674.

Specification of Letters Patent. Patented Jan. 28, 1919.

Application filed September 27, 1915. Serial No. 52,868.

To all whom it may concern:

Be it known that I, HARRY Y. ARMSTRONG, a citizen of the United States, residing at Springfield, in the county of Hampden and 5 State of Massachusetts, have invented certain Improvements in Wrapping-Machines, of which the following description, in connection with the accompanying drawings, is a specification, like reference characters on 10 the drawings indicating like parts in the several figures.

This invention relates to wrapping machines and has among its objects to devise a wrapping mechanism which will wrap satisfactorily, and without any manual change 15 in adjustment, articles varying substantially in dimensions; to provide means for treating the articles prior to their introduction to the wrapping mechanism in a manner designed to facilitate the wrapping operation; and to devise mechanism which will apply glue or other adhesive material neatly to the desired parts of the wrapper.

In the accompanying drawings,

25 Figure 1 is a view partly in side elevation and partly in section, of the more important parts of a wrapping machine embodying this invention;

30 Fig. 2 is a cross sectional view on the line 2—2, Fig. 1;

Figs. 3 and 4 are perspective views of different parts of the wrapping mechanism;

Fig. 5 is a perspective view of a gluing device;

35 Fig. 6 is a plan view showing the tumble box constituting part of the wrapping mechanism;

Figs. 7, 8 and 9 are perspective views showing successive steps in the wrapping 40 and gluing operations;

Fig. 10 is a cross sectional view on the line 10—10, Fig. 6; and

45 Fig. 11 is an elevation of the side of the machine opposite to that shown in Fig. 1, certain parts of the frame being broken out to show more clearly the operating parts of the mechanism.

The machine shown for the purpose of explaining the invention is designed to wrap 50 blocks of sugar of the kind known on the market as "Crystal domino sugar."

In the present instance two lumps or blocks of sugar are wrapped in a single package so that the package may be opened

easily by merely twisting the two lumps 55 relatively to each other. These blocks are usually formed by sawing longitudinally the large flat slabs of sugar as they come from the molds to provide long strips or sticks rectangular in cross section; and these sticks 60 are then split into blocks of the so-called "domino" shape. The top and bottom faces of each lump thus are formed in the splitting operation while the end faces are formed by sawing and the sides by molding. 65 By splitting the sticks in this manner the crystal effect is obtained which would be lost if the sticks were sawed; but the plane of cleavage is so irregular that the blocks vary greatly in thickness. There is also a great 70 variation in the widths and lengths of different lumps so that provision must be made in the wrapping machine for taking care of this extraordinary variation in all three dimensions of the lumps. 75

The wrapping mechanism comprises a tumble box 2 and a wrapping chute 4 which is in line with the pocket of the tumble box when the latter is in its stationary position. The lumps of sugar are brought to the 80 wrapping mechanism on a conveyer belt 6 which is supported by two pulleys, one of which, the driven pulley, is indicated at 8. A stationary stop plate 9 lying at right angles to and overhanging the conveyer belt 85 6 arrests the movement of the line of blocks of sugar as they are advanced toward the machine. The two lumps at the end of this line, that is the one abutting against the stop 9 and the one next to it, are forced simultaneously into the wrapping mechanism by a reciprocating feeder or plunger 10 which slides back and forth in a horizontal plane just above the belt 6. 90

As the feeder 10 advances the two lumps 95 into the wrapping mechanism, it pushes them through a sizing apparatus which serves to scrape off or remove enough sugar from the upper sides of the two lumps to reduce them at least to a certain maximum thickness. This sizing apparatus comprises a horizontal grid or grating 12 made up of several parallel plates or bars supported side by side but spaced from each other, as best shown in Figs. 1 and 2, the top of this grid being substantially level with the pocket in the tumble box and with the upper surface of the conveyer belt 6. Small brackets sup- 100 105 110 115 120 125 130 135 140 145 150 155 160

ported by the machine frame and slotted to receive the plates 12 support them in their proper positions. Immediately above this grid is a file 14 secured by means of a thumb screw 15 in a suitable socket formed in a plate 16 which overlies the feeder 10 and forms the top of the guideway through which the sugar is forced. As shown in Fig. 1 the teeth of this file are raked backwardly resembling somewhat the teeth of a rip saw, and the plane of the points of the teeth is inclined backwardly so that the distance from the upper surface of the grid to the back teeth of the file is less than the distance between the front teeth and the grid. Consequently, as the sugar is forced by the feeder 10 through the sizing device, the teeth of the file will progressively remove material from the upper faces of the lumps, provided of course they have parts which are greater in thickness than the minimum distance between the grid 12 and file 14. A side plate 17, parallel to the plate 9, cooperates with the latter plate to guide the lumps of sugar laterally and these two plates have attached to their forward ends spring plates 18 which serve not only as lateral guides for the sugar after it has passed beyond the ends of the plates 9 and 17 but also operate to center the pair of lumps in the guideway. Usually a rough sorting of the lumps of sugar is made before they are placed on the belt 6 so that lumps which are greatly oversize will not be delivered to the machine. This sizing device serves the very important function in this machine of reducing the thickness of oversize articles to be wrapped to dimensions enabling the machine to handle them satisfactorily. These articles otherwise would become jammed in the machine and interrupt its operation so frequently as to greatly reduce its efficiency.

A paper feeding mechanism, which may be of any convenient character, but in the machine shown is substantially like that shown in Patent No. 1,061,584, granted May 13, 1913, is employed to deliver wrappers of the required size one at a time across the path which the sugar takes as it emerges from the sizing device. A wrapper properly delivered for the wrapping operation is indicated at W in Fig. 1. This wrapper stands just in front of the sizing device so that the plunger 10, as it forces a pair of lumps of sugar through the sizing device and into the tumble box 2, causes them to pick up the wrapper and carry it into the pocket of the tumble box, thus folding it about three sides of the pair of lumps.

This tumble box is of novel construction and comprises a head having a slot formed horizontally through it of a depth substantially equal to the minimum distance between the grid 12 and file 14, this head being mounted on a shaft which is given an inter-

mittent rotatable movement of 180 degrees. A sliding block 20 is mounted in the slot in the tumble box and carries a screw 21 slideable in a slot 22 in one wall of the member 2 which serves to limit the extent of the sliding movement of the block. This block fills substantially half the slot in the tumble box; that is, the block and a package of average size just fill the slot. The block thus forms the bottom of a pocket of suitable dimensions to receive a pair of lumps of sugar with a wrapper partially folded about them. The ends of this pocket are formed by two plates 23 and 24, respectively, which are mounted in said slot at opposite ends of the block 20. These plates carry pivot pins 25 and 26, respectively, which project through slots formed in the walls of the rotatable head in a direction parallel to the axis of rotation of the tumble box and two springs 29 mounted, respectively, on opposite sides of the tumble box connect the pins 25 and 26 and tend to press them and consequently the plates 23 and 24 toward each other. The plates 23 and 24 thus are enabled to swing about the pivots 25 and 26, which lie substantially at the base of the pocket in the tumble box, and also to have a bodily movement toward and from each other.

When the feeder 10 forces a pair of lumps of sugar through the sizing device and into the tumble box 2, they pick up their wrapper just as they enter the tumble box and their movement into the pocket of the tumble box folds the wrapper over their forward edge and the top and bottom faces, as shown in Fig. 7. The block 20 at this time is forward or toward the plunger 10 so that, as the article to be wrapped is moved into the tumble box, it forces the block 20 over into the position in which it is shown in Fig. 6 and at the same time spreads the forward ends of the plates 23 and 24 apart to an extent depending upon the length of the article. These plates 23 and 24 make the first end tucks b (see Figs. 7 and 8) at the forward edges of the end faces of the package. The tumble box is next revolved a half revolution in a clockwise direction. (as the parts are seen in Fig. 1) thus bringing the partially wrapped package in line with the folding chute 4 and folding the trailing end of the wrapper w over the edge of the package which is now forward, and leaving the package in the condition in which it is shown in Fig. 8. When the feeder 10 forces the next package into the tumble box the resultant movement of the block 20 will force the package already in the tumble box into the folding chute 4. Just before the package is ejected from the tumble box a glue dauber applies spots of glue g, Fig. 8, to the package. This dauber comprises a head 30 (see Figs. 1 and 5) mounted to reciprocate in vertical

guideways formed in brackets supported on the machine frame and carrying two fingers 32 which are arranged to move through either one of two pairs of holes 34 formed in the opposite walls of the pocket of the tumble box. This dauber normally rests in a glue tank 36, the fingers 32 being submerged in the glue or other adhesive, but is raised by suitable driving mechanism in time to cause the fingers 32 to enter the apertures 34 while the package is in the tumble box and in the condition shown in Fig. 8. These fingers apply the spots *g* of glue to the package just before another package is forced into the tumble box by the feeder 10. This movement carries the package already in the tumble box into the folding chute 4, thus folding the depending flap *f*, Fig. 8, over the bottom of the package and into contact with the glue spots *g*. In order to prevent the glue spots *g* from smearing on the walls of the tumble box, as the package is ejected therefrom, these walls are grooved or cut away in front of the apertures 34, as indicated at 35, Fig. 6.

The folding chute is of novel construction and comprises a bottom plate 40 supported on small brackets projecting from the machine frame and a top plate 42 that is removably supported on the bottom plate 40 by means of dowel pins 43. A swinging arm 41, normally is clamped in the position shown in Fig. 1 in which it holds the plate 42 in its operative position, but may be loosened to allow the plate to be removed. The upper plate 42 supports a pair of end tuckers 44 and 45, respectively, mounted at opposite sides of the package passage through the chute and provided with oppositely bowed arms that are pivoted to lugs on the plate so that the tuckers can swing toward and from each other. The construction of these parts is clearly shown in Fig. 3. A coiled spring 46 loosely encircles a rod 47 which slides freely through holes formed in lugs projecting from the tucker arms above their pivots and this spring presses the tuckers yieldingly toward each other, the movement of these members under the influence of the spring 46 being limited however by heads on the opposite ends of the rod 47. These tuckers operate to make the tucks *c*, Fig. 9, at opposite ends of the package corresponding to the tucks *b* made by the plates 23 and 24.

Two lower and upper pairs of pointed flaps *d* and *e*, respectively, now remain projecting from the opposite ends of the package. The two lower flaps *d* are folded against the ends of the package (the folded position of one of these flaps being shown in Fig. 9) by means of lower folders 48 and 49, respectively, which are constructed as shown in Fig. 4 and are carried by the lower plate 40. The folder 48 is slidably mounted

on a pair of rods 50 that project horizontally from the plate 40 and each of these rods is encircled by a coiled spring 51 which holds the folder 48 yieldingly against the plate 40 but permits it to be moved outwardly by the package as the latter is forced through the folding chute. The opposite folder 49 is supported in the same manner and is backed up by springs corresponding to the springs 51.

A pair of top folders 52 and 53, respectively, (Fig. 3) are pivoted to the upper plate 42 at 54 and 55, respectively, so that they can swing toward and from each other and are loosely connected at their upper ends by a rod 56 which is encircled by a spring 57 that tends to force the two folders 52 and 53 yieldingly toward each other, this movement however being limited by heads on the opposite ends of the rod 56. These folders turn down the two upper pointed flaps *e* projecting from the opposite ends of the package and complete the folding operation.

It will be evident from the foregoing description that each pair of tucking or folding members carried by the plates 40 and 42 are mounted to have a considerable yielding movement toward and from each other so that these members can readily adjust themselves to packages varying substantially in dimensions. Just after the lower flaps *d* have been folded against the ends of the package by the folders 48 and 49 and while the flaps *e* are projecting over the upper edges of the folders 48 and 49, the glue dauber 30 is raised and applies spots of glue to each of the flaps *e*, as indicated at *h* in Fig. 9. This application of glue is effected by two glue applying fingers 60 formed far enough apart on the glue dauber head 30 to straddle the folding chute, so that they are operative to apply glue to a package in the folding chute at the same instant that the fingers 32 place the spots of glue *g* on a package positioned in the tumble box 2. A pair of rolls, one of which is indicated in Fig. 3 at 62, working in slots 63 in the plate 42 and held downwardly by a leaf spring, may be used if found necessary as a friction means to prevent any displacement of the package due, for instance, to momentum, after the package has once been moved into the folding chute. Experience has indicated, however, that this device is needed only under extraordinary conditions.

The wrapping operations on a package now being completed, it is next forced out of the wrapping chute by packages behind it into the space between a pair of driven chains 64 which maintain pressure on the end folds of the package while the glue is drying. A brush 66 also holds the flap *f* in place for the same purpose, a presser plate, not shown, being provided to maintain

pressure on the packages while they are being advanced through this drying mechanism.

The operating mechanism for the moving parts above described may be of any convenient character and any detailed description of it is believed to be unnecessary. In general it resembles very closely that shown in my co-pending application Serial No. 656,504, filed October 24, 1911. Briefly stated and referring to Fig. 11, this mechanism comprises a main shaft 68 which is driven from any convenient source of power, and carries a crank that operates a slotted lever 70 which is fulcrumed at 71 and reciprocates the head 72 of the plunger 10. A chain 74, driven by a sprocket on the main shaft 68, operates the driver of a Geneva wheel 75 which has a geared connection with a shaft 76 on the end of which the tumble box 2 is mounted. This Geneva drive operates to give the tumble box 2 a series of half revolutions as above described. Another chain 78, driven from the shaft on which the Geneva driver is mounted, operates a shaft 79 on which the wrapper stripper is mounted. The shaft of the Geneva driver also has a geared connection with a shaft 80 which operates through bevel gears 82 to drive the pulley 8 on which the conveyer belt 6 runs. The glue dauber 30 has an operative connection with one arm of a bell crank lever 84 which is fulcrumed in the machine frame at 85 and has its other arm connected to a cam follower 86 that is operated by a cam fast on the main driving shaft 68. The sprockets which drive the chains 64 are operated by a spiral gear connection with a shaft 88, (see Fig. 1) which is driven by a sprocket and chain connection with a shaft 90 (see Fig. 11,) the chain being indicated at 91, and the latter shaft being driven by a sprocket and chain connection with the main shaft 68. The particular operating mechanism used for these parts is of course merely a matter of mechanical design and the above description is given simply for the purpose of making the disclosure more complete.

Having thus described my invention, what I claim as new and desire to secure by Letters Patent of the United States is:

1. In a machine for wrapping lumps of sugar, the combination with wrapping mechanism, of means for feeding a predetermined number of lumps of sugar at a time to said wrapping mechanism, and sizing means co-operating with said feeding means to reduce the size of oversized lumps prior to their presentation to said wrapping mechanism by said feeding means.

2. In a machine of the character described, the combination with wrapping mechanism, of means for feeding articles to be wrapped one at a time to said mech-

anism and sizing means co-operating with said feeding means to reduce the size of oversized articles prior to their presentation to said wrapping mechanism by said feeding means, said sizing means being constructed and arranged to reduce the size of oversized articles by removing material from said articles.

3. In a machine of the character described, the combination with wrapping mechanism, of a reciprocating feeder operative to present articles to be wrapped one at a time to said wrapping mechanism and means for reducing the dimensions of oversized articles by removing material from them, said means being positioned in front of said wrapping mechanism and in the path of said articles as they are pushed into said wrapping mechanism by said feeder.

4. In a machine of the character described, the combination with wrapping mechanism, of a reciprocating feeder operative to present articles to be wrapped one at a time to said wrapping mechanism and sizing mechanism for said articles through which the articles are pushed one at a time by said feeder, said sizing mechanism comprising a grating over which the articles are moved and a file positioned above said grating and operative to remove surplus material from the articles.

5. In a wrapping machine, a tumble box, having a pocket constructed to receive an article with a wrapper partially folded about it, and two plates forming the opposite ends of the pocket and mounted to have a yielding bodily movement away from each other and to swing toward and from each other about axes located substantially at the opposite ends of the bottom of the pocket.

6. In a wrapping machine, a tumble box, having a pocket constructed to receive an article with a wrapper partially folded about it, and two plates forming the opposite sides of the pocket and mounted to have a yielding bodily movement away from each other and to swing about axes extending parallel to the depth of the pocket, whereby said plates may be moved by a package as it is inserted in said pocket.

7. In a wrapping machine, a tumble box having a pocket constructed to receive an article with a wrapper partially folded about it, and two plates forming the opposite sides of said pocket, said plates being movable about independent pivots mounted to slide in the tumble box toward and from each other, and springs acting on said pivots to hold them yieldingly toward each other.

8. In a wrapping machine, a tumble box, comprising a rotatable head having a slot formed therethrough, a block slidably mounted in said slot but filling only part of said slot whereby it forms the bottom of a pocket for an article having a wrapper par-

- tially folded about it, and two plates mounted in said slot at opposite ends of said block and between which the block slides, a substantially central pivot carried by each 5 of said plates, said pivots being mounted for sliding movement toward and from each other in said head and springs acting on said pivots to hold said plates yieldingly toward each other.
- 10 9. In a wrapping machine, a folding chute comprising a bottom plate, a top plate removably supported on said bottom plate, a pair of end tuckers supported by one of said plates, a pair of top folders supported by 15 the top plate, a pair of bottom folders supported by the bottom plate, the members of each of said pairs being supported for yielding movement relative to each other, and means for holding said top plate in its normal position constructed and arranged to be 20

moved into either a plate holding or a plate releasing position.

10. In a wrapping machine, the combination with a folding chute, of a tumble box adjacent thereto, means for advancing articles to be wrapped from one of said devices to the other, and a glue dauber having fingers constructed and arranged to apply glue to a package in the tumble box and simultaneously to apply glue to another package 25 in the folding chute, and means for operating said dauber.

In testimony whereof I have signed my name to this specification in the presence of two subscribing witnesses.

HARRY Y. ARMSTRONG.
